UNITED STATES PATENT OFFICE

144,427

DESIGN FOR A HEAD FOR A HOBBY HORSE OR SIMILAR ARTICLE

Darwin C. Stanley, Compton, Calif.

Application April 9, 1945, Serial No. 118,932

Term of patent 14 years

(Cl. D34—15)

To all whom it may concern:

Be it known that I, Darwin C. Stanley, a citizen of the United States, residing at Compton, in the county of Los Angeles and State of California, have invented a new, original, and ornamental Design for a Head for a Hobby Horse or Similar Article, of which the following is a specification, reference being had to the accompanying drawing, forming part thereof.

Fig. 1 is a top plan view of a head for a hobby horse showing my new design; and

Fig. 2 is a side elevational view thereof.

The side opposite of that shown in Fig. 2 presents the appearance shown.

I claim:

The ornamental design for a head for a hobby horse or similar article, as shown and described.

DARWIN C. STANLEY.
